OUTBOARD MOTOR

Thor Hansen, Cedarburg, Wis.

Application November 18, 1935, Serial No. 50,353

6 Claims. (Cl. 115—17)

This invention relates to improvements in outboard motors and has as an object to provide an improved construction for motors of this type by which a material reduction in weight and cost is effected.

In this connection, it is a further object of the invention to provide a motor of the character described so constructed that castings are practically eliminated through the use of steel stampings.

Another object of this invention is to provide an outboard motor of improved design to facilitate assembly and to reduce the number of parts. Another object of this invention is to provide an outboard motor of exceptionally strong and rugged construction.

Another object of this invention is to provide a novel manner of keeping the exhaust manifold of the motor cool.

Another object of this invention is to provide an improved carburetor for outboard motors. A further object of this invention is to provide an outboard motor having better balance to facilitate carrying the same.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a side view of an outboard motor constructed in accordance with this invention, with parts of the exhaust manifold broken away and in section;

Figure 2 is a front view of the motor taken on the plane of the line 2—2 of Figure 1;

Figure 3 is a vertical section view taken through Figure 1 on the plane of the line 3—3;

Figure 4 is a vertical section view taken through Figure 2 on the plane of the line 4—4;

Figure 5 is a perspective view of one of the sections of the propeller shaft housing;

Figure 6 is a perspective view of the two complementary sections forming the crank case;

Figure 7 is a perspective view of the cylinder casting;

Figure 8 is a perspective view of the upper end portion of the exhaust manifold;

Figure 9 is an enlarged vertical section view through Figure 3 on the plane of the line 9—9;

Figure 10 is a vertical cross section view through the carburetor; and

Figure 11 is a view similar to Figure 4, but on an enlarged scale.

Referring now more particularly to the accompanying drawings in which like numerals indicate like parts throughout the several views, the numeral 6 indicates generally the engine portion or head of the motor, and the numeral 6 indicates the propeller portion. A torque tube 7 rigidly and permanently connects the engine portion or head 6 with the propeller portion 6, and to mount and attach the motor on a boat, a mounting bracket, indicated generally by the numeral 8, is provided.

The engine portion or head 6 comprises a cylinder 9 and a crank case 10. Within the crank case 10 is a crank shaft 11 having an intermediate crank portion 12 provided by two spaced discs 13 and 14 joined by a crank pin 15. Fixed to the discs 13 and 14, respectively are upper and lower axially aligned shafts 16 and 17. The upper shaft 16 mounts a fly-wheel 18 within which a magneto 19 of conventional construction is housed. The lower shaft 17 is coupled to a drive shaft 20 which is disposed within the torque tube 7 to extend down into a propeller shaft housing 21 to provide a driving connection between the crank shaft and a propeller shaft 22.

Within the cylinder 9 is a piston 23 connected with the crank pin 15 by a connecting rod 24. The cylinder and the piston are the only major castings in the entire motor. All of the other important elements which usually are castings are steel stampings, as will be hereinafter more fully described.

The cylinder 9 is provided with a water jacket 25 having an inlet 26 at the bottom of the cylinder and an outlet 27 at one side of the cylinder. As is customary, a spark plug 28 is secured in the cylinder wall and is connected with the magneto by a conductor 29. The usual hand control lever 30 for advancing the spark and for interrupting the ignition circuit is attached to the magneto structure to project forwardly, as shown in Figure 1.

Above the cylinder is a gas tank 31 mounted by means of supporting feet 32 fixed to the bottom of the tank and attached to the cylinder. A carburetor 33 is mounted directly on the crank

case 10 opposite the cylinder 8 and has a fuel feed line 34 connecting it with the gas tank.

The engine is of the two-cycle type drawing the fuel charge into the crank case upon the up-stroke of the piston and exhausting the spent charge through an exhaust port 35 opening to the same side of the cylinder at which the water jacket outlet 27 is located. Secured to this side of the cylinder, which is machined as shown in Figure 7, is an exhaust manifold 36. The exhaust manifold comprises a casting 37 having an upper portion 38 arranged to be bolted to the side of the cylinder with a cored opening 39 in register with the exhaust port 35 and another cored opening 40 in register with the outlet port 27 from the water jacket.

Beneath its upper end portion 38, the manifold casting is directed inwardly at an angle so as to dispose its lower end portion underneath the cylinder and substantially in line with the inlet port leading to the water jacket. The cored opening 40, which registers with the outlet port of the water jacket, communicates with a cored passage extending down past the cored opening 39 into the lower tubular portion of the manifold casting so that water entering the cored opening 40 cannot enter the cylinder through the exhaust port.

The lower end of the casting 37 has a tube or exhaust pipe 41 fixed thereto which extends straight down beneath the cylinder and directly to the rear and parallel to the torque tube 7 to have its lower discharge end beneath the water line when the motor is in use. Within the tube 41, which conducts both the exhaust gases and the exhaust water from the water jacket down beneath the water line, is a feed water pipe 42. This pipe extends up through the entire length of the exhaust pipe 41 and has its upper end attached to the inlet port 26 and its lower end connected with a water pump 43 located between the propeller shaft housing and a screw propeller 44 fixed to the propeller shaft. Hence, water will be pumped up through the feed pipe 42 into the water jacket to circulate through the water jacket of the cylinder to the exhaust manifold.

The propeller shaft is journaled in bearings 45 and 46 mounted in the housing 21 and fixed to the propeller shaft between these two bearings is a bevel gear 47. The bevel gear 47 meshes with a pinion 48 fixed to the lower end of the drive shaft 20, which lower end portion of the drive shaft is journaled in a bearing 49 also mounted in the propeller shaft housing.

In the present invention, unlike past outboard motors, the propeller shaft housing comprises two complementary sections in the form of steel stampings 50 (see Figure 5). These sections 50 are formed with cavities 51, which together form a chamber in which the meshing bevel gears 47 and 48 are located. Communicating with the cavity 51 of each section are semi-cylindrical channels or depressions 52 and 53. With the sections 50 secured together, these semi-cylindrical channels form axially aligned bores for the reception of the bearings 45 and 46, respectively. The dimensions of the channels are such that when the two plate-like sections 50 are clamped together with a gasket 54 therebetween, the bearings 45 and 46 are securely gripped.

Besides being held against relative motion with respect to the housing by being gripped between the two sections 50, the bearings are positively held against endwise displacement. The bearing

45 has one end abutting the face of the bevel gears 47 and its other end abutting the closed end of the channel 52, and the bearing 46 has its inner end abutting the hub of the bevel gear 47 and has a flange 55 engaging the shoulder at the juncture of the cavities 51 and the channels 46.

Besides the channels 45 and 46, the housing sections 50 have another semi-cylindrical channel 56 formed therein at right angles to the propeller shaft and in which the drive shaft and torque tube are disposed. This semi-cylindrical channel 56 has an outer portion of a diameter to snugly grip the torque tube when the housing sections 50 are secured together and is abruptly reduced in diameter near its lower end to provide a shoulder against which the bearing 49 seats, the bearing 49 being in the form of a bushing slipped into the lower end of the torque tube with a flange on the extreme lower end thereof, the outside diameter of which is equal to that of the torque tube.

The marginal edge portions of the housing sections 50 provide flanges between which the gasket 54 is clamped upon securement of the sections together by bolts 57, and it is to be observed that these flanges are of such size and so shaped as to provide a downwardly extending fin 58 for the protection of the propeller screw and to also serve as a rudder.

Upon assembly of the propeller shaft and drive shaft with the torque tube in one-half of the housing 21 and the securement of the other half thereto, these parts are permanently and quickly secured in assembled relationship, and while the clamping action of the housing sections onto the torque tube serves to lock the torque tube to the housing, relative movement of these parts may be positively precluded by a cap screw 59 threaded in one section 50 and entering a hole in the torque tube.

Obviously, the chamber formed by the cavities 51 in which the meshing bevel gears are located may be packed with a suitable lubricant at the time of assembly and additional lubricant may be supplied through the openings in which the cap screw 59 is secured.

The crank case 10, like the propeller shaft housing, comprises two complementary steel stampings 60 and 61. The section 60 has a deep cavity 62 formed therein with upwardly and downwardly extending axially aligned semi-cylindrical channels 63 and 64, respectively, communicating with the deep cavity. The bottom of the cavity 62 has an oblong hole 65 therethrough and two attaching screws 66 are secured to the wall of the cavity at opposite sides of the hole 65. The hole 65 registers with the discharge port 67 of the carburetor 38 which it attached to the crank case by means of the screws 66. The screws 66 pass through drilled holes in a flange on the carburetor and have securing nuts mounted thereon to clamp the carburetor flange to the front of the crank case, as shown.

The crank case section 61, like the section 60, has a deep cavity 68 formed therein, the bottom of which is open, and also has upwardly and downwardly extending axially aligned semi-cylindrical channels 69 and 70, respectively. Welded to the outside of the section 61 over the hole in its deep cavity is a heavy metal ring 71 provided with tapped holes 72 to receive cap screws by which the cylinder casting is attached to the crank case. The flanges 73 on the crank case sections 60 and 61 have aligned holes for the reception of bolts 74 by which the two sections are

clamped together with a gasket 76 interposed therebetween.

When the two crank case sections are secured together, the semi-cylindrical channels 68 and 69 coact to form a bore for the reception of a bearing structure 78 in which the upper end 16 of the crank shaft is journalled. It is to be observed that the bearing structure 78 has a flange 77 at its lower end which engages the shoulder at the juncture of the channels 68 and 69 with their respective deep portions 62 and 63 so that the bearing structure is positively held against outward endwise movement. The lower end of the bearing structure bears against the disc 13 and thus serves to hold the crank shaft against upward endwise movement.

The channels 64 and 70 of the crank case sections 69 and 61, respectively, embrace and snugly grip the upper end of the torque tube 7. Fixed in the upper end of the torque tube is a bearing bushing 78 in which the lower end 17 of the crank shaft is journalled. The bearing bushing 78, like the bearing structure 78, is provided with a flange 79 to engage the shoulder at the juncture of the channels 64 and 70 with their adjacent deep portions, and the upper end of the bushing also engages the disc 14. Consequently, when these parts are assembled with the crank case sections and the sections clamped together, the entire structure will be held against relative endwise motion and will be maintained properly assembled.

The lower extremity 80 of the crank shaft and the upper end 81 of the drive shaft are square, and telescoped over these square ends is a coupling 82 through which the crank shaft and the drive shaft are connected. A sleeve 83, preferably encircles the collar 82, although this is not essential.

As in the case of the propeller shaft housing, the securing of the crank case sections together grips the torque tube and securely connects these two parts. However, to positively preclude the possibility of relative shifting between the torque tube and the crank case, a cap screw 84 is threaded in the crank case section 61 and enters aligned holes in the torque tube and the sleeve 83. A similar cap screw 85 may be provided to positively lock the bearing structure 78 against relative motion with respect to the crank case.

The mounting bracket 8 includes a sleeve 86 in which the torque tube 7 is journalled. The sleeve 86 forms part of a casting having spaced parallel arms 87 attached to the sleeve at opposite sides thereof and extending upwardly and forwardly to be pivotally connected to a frame 88 by means of a bolt 89. The frame 88 is of any suitable construction and is designed to be clamped to a support which is generally the rear of a boat, a clamping screw 90 being provided for this purpose.

The weight of the motor is supported on the sleeve 86 by having the lower end of the crank case, specifically the lower ends of the channels 64 and 70 which form integral parts of the crank case, engaging and resting on the upper end of the sleeve, and to prevent sliding of the torque tube in the sleeve, a collar 91 is secured to the tube beneath the sleeve. In this manner, the entire motor is conveniently supported from the mounting bracket in a manner permitting turning about the axis of the torque tube for the purpose of steering. To facilitate such turning of the motor in its mounting bracket, a handle 92 is secured to the crank case preferably by two of the bolts 74.

It is to be observed that the carburetor is

mounted on the front of the motor where it is readily accessible, and that its discharge port opens directly into the crank case.

The carburetor itself is of novel construction. As best shown in Figures 9 and 10, the carburetor 5 comprises a housing 93 having an open air inlet port 94 and a mixing chamber 95 with a valve seat 96 interposed between the air inlet port 94 and the mixing chamber. The discharge port 61 communicates with the mixing chamber and conducts the combustible mixture directly into the crank case of the engine.

Opening to the valve seat is a liquid fuel orifice 97 to which liquid fuel is conducted by the feed line 34, a needle valve 98 being provided to control the flow of fuel to the orifice. Inasmuch as the orifice opens directly to the valve seat, it may be closed by a valve 99 arranged to engage the seat 96. The valve is slidably mounted in the carburetor body by means of a stem 100 riding in a vertical bore 101.

The valve 99 is inserted into the body of the carburetor through a hole 102 in the top of the mixing chamber which is closed by a cap 103 threaded therein. A spring 104 confined between the top of the valve 99 and the cap 103 yieldingly urges the valve 99 closed shutting off the supply of air and liquid fuel to the engine. The spring 104 is of such strength that upon the development of engine suction in the mixing chamber, the valve will be lifted to allow air and fuel to enter the mixing chamber and from there to be drawn into the crank case. The lift of the valve is proportional to the degree of engine suction. In this manner, an exceedingly simple carburetor is provided in which the only moving part is the valve 35 lifted in response to engine suction.

From the foregoing description taken in connection with the accompanying drawings, it will be readily apparent to those skilled in the art to 40 which this invention appertains, that this invention provides an outboard motor of simple and sturdy construction with many advantages over past outboard motors of the same class.

What I claim as my invention is:

1. In an outboard motor including a crank shaft, a propeller shaft, and a drive shaft for connecting the crank shaft and the propeller shaft, a torque tube enclosing the drive shaft, a propeller shaft housing, and a crank case, said 50 propeller shaft housing and crank case each comprising complementary sections adapted to be clamped together, and said sections of the propeller shaft housing and the crank case being clamped to the torque tube by the same clamping 55 action that secures the sections together whereby said torque tube permanently joins the propeller shaft housing and the crank case.

2. In an outboard motor including a crank shaft, a propeller shaft, a drive shaft for connecting the crank shaft and the propeller shaft, a torque tube enclosing the drive shaft, a crank case and a propeller shaft housing, said crank case and propeller shaft housing both being of split construction and each comprising two complementary sections adapted to be connected together on a plane coinciding with the axis of the drive shaft, and both the crank case and propeller shaft housing having portions adapted to embrace and grip the torque tube upon securing of their 70 sections together whereby assembly of said units also secures them to the torque tube.

3. In an outboard motor including a crank shaft, a propeller shaft, a drive shaft for connecting the crank shaft and the propeller shaft, a 75

propeller shaft housing, a torque tube attached to the propeller shaft housing and enclosing the drive shaft and one end portion of the crank shaft, a bearing carried by the torque tube in which said end of the crank shaft is journalled, and a crank case enclosing the crank shaft and having a portion embracing the adjacent end portion of the torque tube.

4. In an outboard motor including a crank shaft, a propeller shaft, a drive shaft for connecting the crank shaft and the propeller shaft, a propeller shaft housing, a torque tube attached to the propeller shaft housing and enclosing the drive shaft and one end portion of the crank shaft, a bearing carried by the torque tube in which said end of the crank shaft is journalled, and a crank case enclosing the crank shaft and having a portion embracing the adjacent end portion of the torque tube, said crank case comprising complementary sections joined on a plane coinciding with the axis of the crank shaft and torque tube so that upon securement of the complementary sections of the crank case together its portion embracing the torque tube is clamped to the torque tube.

5. In an outboard motor including a crank shaft, a propeller shaft and a drive shaft for connecting the crank shaft and the propeller shaft, a crank case comprising two complementary sections joined on a plane passing longitudinally through the axis of the crank shaft and drive shaft, each of said crank case sections being formed with a deep cavity for the reception of the crank portion of the crank shaft and semi-cylindrical channels axially aligned and communicat-

ing with the deep cavity for the reception of crank shaft bearings, a crank shaft bearing having a bore in which one end portion of the crank shaft is journalled, said crank shaft bearing being clamped in the semi-cylindrical channels of the two sections at one end of the deep cavity, and a torque tube enclosing the drive shaft and clamped in the other semi-cylindrical channels of the crank case sections, said torque tube having a bearing in which the other end portion of the crank shaft is journalled.

6. In an outboard motor including a crank shaft, a propeller shaft and a drive shaft for connecting the crank shaft and the propeller shaft, a crank case comprising two complementary sections joined on a plane passing longitudinally through the axis of the crank shaft and drive shaft, each of said crank case sections being formed with a deep cavity for the reception of the crank portion of the crank shaft and semi-cylindrical channels axially aligned and communicating with the deep cavity for the reception of crank shaft bearings, a crank shaft bearing having a bore in which one end portion of the crank shaft is journalled, said crank shaft bearing being clamped in the semi-cylindrical channels of the two sections at one end of the deep cavity, a torque tube enclosing the drive shaft and clamped in the other semi-cylindrical channels of the crank case sections, said torque tube having a bearing in which the other end portion of the crank shaft is journalled, and means to positively prevent outward endwise movement of the torque tube with respect to the crank case.

THOR HANSEN.
